UNITED STATES PATENT OFFICE.

CHARLES M. BULLER, OF MILWAUKEE, WISCONSIN, ASSIGNOR TO L. J. MUELLER
FURNACE COMPANY, OF MILWAUKEE, WISCONSIN, A CORPORATION OF WIS-
CONSIN.

PIPELESS FURNACE.

1,422,828.

Specification of Letters Patent. Patented July 18, 1922.

Application filed November 12, 1919. Serial No. 337,553.

To all whom it may concern:

Be it known that I, CHARLES M. BULLER, a citizen of the United States, and resident of Milwaukee, in the county of Milwaukee and State of Wisconsin, have invented new and useful Improvements in Pipeless Furnaces, of which the following is a description, reference being had to the accompanying drawings, which are a part of this specification.

10 The present invention relates to certain new and useful improvements in heating furnaces of the hot air conductor type in which cold and hot air ducts have coincident terminals above the heater, and refers more particularly to the furnace section or dome connecting the heat chamber proper with the terminal.

As the dome sections connecting the heat chamber proper with the terminal are generally substantially cone-shaped it has been the custom to construct the same by means of a strip of metal cut in an arc so that when the ends thereof are brought together they will form a tubular section having inclined walls. This method of constructing the sections is extremely unsatisfactory as there is a considerable wastage of material due to the cutting of a blank on an arc, and with this in mind my invention has for one of its 30 objects to provide a furnace section of the class described, so constructed as to eliminate all wastage.

Another object of my invention is to provide a furnace section of the class described which will be formed from a substantially rectangular sheet or blank of material crimped or plaited to give the desired inclination to the walls and at the same time substantially reinforce the same.

40 A further object of this invention is to provide a furnace section of the class described employing two complementary sections constructed as described and nested to provide a hot air passageway surrounded by 45 a dead air space.

A still further object of the present invention is to provide a furnace section of the type described in which the section is readily interchangeable with furnaces of the 50 same type of various sizes, and which will be of simple construction and extremely inexpensive to produce.

With the above and other objects in view which will appear as the description proceeds, my invention resides in the novel con-

struction, combination and arrangement of parts, substantially as hereinafter described and more particularly defined by the appended claims, it being understood that such changes in the precise embodiment of the 60 herein disclosed invention may be made as come within the scope of the claims.

In the accompanying drawings I have illustrated two complete examples of the physical embodiment of my invention constructed according to the best modes I have so far devised for the practical application of the principles thereof, and in which:

Fig. 1 is a sectional view through the upper portion of a heating furnace employing 70 my novel form of furnace section providing a hot air passageway.

Fig. 2 is a sectional view taken through my novel form of furnace section on the line 2—2 of Fig. 1.

75 Fig. 3 is an enlarged fragmentary view taken on the line 3—3 of Fig. 2.

Fig. 4 is a plan view of rectangular blank employed in forming the furnace section.

Fig. 5 is a side plan view of a slightly 80 modified form of my furnace section.

Fig. 6 is an enlarged fragmentary sectional view taken through a portion of the upper half thereof on the line 6—6 of Fig. 5, and

85 Fig. 7 is a top plan view thereof.

As illustrated the furnace is of well-known type wherein the heater is surrounded by casings constituting two chambers, one the hot air chamber for conducting the 90 hot air upwardly, and the other, a cold air chamber for conducting the cold atmosphere downwardly and communicating with the hot air chamber at the base thereof.

A drum including two spaced apart casings 10 surround the heater (not shown) and have their upper ends retained in spaced relation by means of an upper ring or hook 11 centrally provided with a laterally extending annular rib or re-inforcing flange 12 100 having a plurality of U-shaped members 13 engaging the inner casing 10 as best shown in Fig. 2.

The drum formed by the casings 10 provides a heating chamber surrounding the 105 heater (not shown) and said heating chamber is supplied with cold air by means of an air passage way 14 having an inlet 15 co-incident with the hot air outlet as will be later described.

My improved form of dome section 16 has its lower end in snug engagement with the ring 11 and has its upper end connected with a register plate 17 by means of a pipe section 18, the register plate 17 also having the inlet 15 therein for the cold air passage way 14. The dome 16 is of novel construction and is formed of two complementary sections 19 each formed from a single sheet or rectangular blank of material 20 the ends of which have been secured together to provide a plain open ended cylinder which is then placed in a stamping machine and ribbed or plaited as at 21 whereby the walls are inclined upwardly and inwardly. The ribs 21, besides giving the desired shape to the sections 19, form re-inforcing means for the drum as will be at once apparent. The upper smaller ends of the sections are beaded 20 as at 22 and the portions above the beads 22 are directed upwardly in a straight line as at 23 for receiving the lower end of the pipe 18, the beads 22 limiting the engagement of said pipe with the drum section. The lower 25 ends of the section 19 are struck laterally and then downwardly as at 24 to provide flanges for engaging the annular ring 11.

The dome 16, as before stated, consists of two of the sections 19 nested together as best shown in Figs. 1 and 2 whereby a stronger structure is had having the walls thereof separated by a dead air space 25. The dead air space 25 is provided by the bead 22 of the innermost section 19 abutting 30 the adjacent wall portion of the outermost section 19, preventing the walls of the same from engaging, and the downwardly extending flanges 24 of the sections are engaged, as shown in Fig. 2. The top edge 40 of the portion 23 of the outmost section 19 is preferably turned inwardly a slight distance for convenience in fitting the pipe section 18 thereon.

Heretofore, it has been common practice 45 to form the dome 16 from a blank of material so cut that when its ends are brought together and riveted or otherwise secured, a dome is formed provided with upwardly and inwardly inclined walls. This method 50 is extremely wasteful in material in that, to cut the blank in the desired shape, the longitudinal edges of the blank must be curved, and consequently when cut from a sheet of material of a given size, the number 55 obtained from one sheet is greatly reduced and the material cut away is a complete loss, being of no use whatsoever.

Consequently one of the main advantages 60 obtained by my method of forming the dome 16, is that the waste of material is practically nil, and a great number of blanks may be cut from a single sheet of material. As hereinbefore described I form 65 the dome 16 from a single blank of material of rectangular form which may be

of one piece or of several pieces secured together, to form a plain cylindrical casing which is then plaited or ribbed to provide the inclined walls. This method of constructing the dome 16 also provides a reinforced dome as will be obvious. 70

In Figs. 5, 6, and 7 I have employed a slightly modified form of my invention in which the dome section has a lower portion similar to that type of my invention described having inclined walls and has an upper section of rectangular shape for engagement with a rectangular pipe or else which may be adapted to receive directly the grating 17. 75

What I claim for my invention is:

1. A section for a heating furnace consisting of a tapered tubular casing having longitudinally extending reinforcing plaits in spaced relation, the plaits at the end of the casing of less size being of greater width than at the other or larger end of the casing, said casing having a medial circumferentially extending rib and an end flange. 80

2. A section for a heating furnace consisting of a tapered tubular casing having longitudinally extending reinforcing plaits in spaced relation, the plaits starting adjacent the larger end of the casing and gradually increasing in width towards the end of the casing of less size, said casing having a medial circumferentially extending rib and an angular end flange. 90

3. A section for a heating furnace consisting of a tapered tubular casing having longitudinally extending reinforcing plaits in spaced relation, the plaits starting adjacent the larger end of the casing and gradually increasing in width towards the end of the casing of less diameter, said casing having a circumferentially extending rib near its end of smaller size and an outwardly and downwardly extending flange at its end of larger size. 100

4. A section for a heating furnace consisting of two tapered tubular casings having longitudinally extending reinforcing plaits in spaced relation, the plaits starting adjacent the larger ends of the casings and gradually increasing in width towards the ends of the casings of less diameter, said casings having circumferential ribs near their ends of smaller size and also having outwardly and downwardly extending flanges at their ends of larger size, one of said casings extending around the other in spaced relation with the flanged portions in intimate contact, the opposite ends of the casings also being in engagement with each other and with the outer casing contacting with the annular rib of the inner casing. 110

5. A section for heating furnaces, comprising two complementary casings, longitudinally extending plaits formed in each 120

casing to form reenforcing ribs and inclined walls, a circumferentially extending rib formed in each casing near one end, and a flange formed on each casing near the other end, said casings being nested and the rib of the inner casing retaining the intermediate wall portions of the casing in

spaced relation and the flange of the outer casing abutting the flange of the inner casing to provide an air space therebetween 10 closed at both ends.

In testimony whereof, I affix my signature.

CHARLES M. BULLER.
